UNITED STATES PATENT OFFICE.

WILHELM UMLAND, OF NEW YORK, N. Y.

UPRIGHT-PIANO CASE.

SPECIFICATION forming part of Letters Patent No. 324,051, dated August 11, 1885

Application filed May 23, 1885. (No model.)

To all whom it may concern:

Be it known that I, WILHELM UMLAND, of the city of New York, county and State of New York, have invented a new and Improved 5 Music-Rest for Upright Pianos, of which the following specification is a full, clear, and exact description.

This invention relates to a new music-rest for upright pianos, which will be automatic- 10 ally put in the proper inclined position upon the opening of the lid or fall.

The invention consists in the various features of improvement hereinafter more fully pointed out.

15 In the accompanying drawings, Figure 1 is a front view of an upright piano-forte provided with my improvement, showing the lid open. Fig. 2 is a vertical transverse section of the same with the lid closed, and Fig. 3 a rear view of the front plate.

20 The letter A represents an upright piano-forte of customary or suitable construction. a is the front plate, and b the lid, fall, or cover, adapted to close over the keys. The plate a is made with a large central opening of square or other shape, into which is fitted a panel, c, of a size and shape corresponding to that of the opening. This panel turns on pivots that engage bearings at the back of plate a, as shown 25 in Fig. 3. The panel c is provided near its upper edge with a rearwardly-extending lug, d, against the forward face of which bears one end of a lever, e, pivoted to a cross-piece, f. The lower free end of the lever e is placed op- 30 posite to a pin, g, which is free to slide back- ward and forward within a groove formed in the frame A, and opening directly back of lid b, as seen in Fig. 2. h is a spring placed between frame A and the upper arm of lever

e, and having a tendency to throw such arm 40 rearwardly. A small pin or stop, i, may be sunk into edge of lid b opposite to the pin g, if desired. j is a rest attached to the lower face of lid b, and serving to support the bottom of the music when the lid is swung up. 45

The operation of the device is as follows: When the lid b is down, (full lines, Fig. 2,) it pushes pin g backward, and this pin in turn causes the upper arm of lever e to be swung forward. The front edge of this lever-arm 50 will now bear against the rear face of panel c, and thereby hold such panel in its proper vertical position to close the opening in front plate, a. On the raising of lid b, the spring h will be free to throw the upper arm of lever e 55 backward, as the pin g may be pushed forward by the lower lever-arm. The upper lever-arm, bearing against lug d, will cause the panel c to be swung on its pivots and to assume the inclined position indicated by dotted lines in 60 Fig. 2. In this position the panel serves to support the upper portion of the music, the lower portion of which is supported on the rest j. In this way the entire music-rest is automatically put into and out of position on 65 the opening or closing of the lid.

I claim as my invention—

1. The combination of open face-plate a with panel c, lid b, lever e, spring h, and pin g, substantially as specified. 70

2. The combination of open face-plate a with panel c, lid b, stop d, lever e, spring h, and pin g, and cross-piece f, substantially as specified.

WILHELM UMLAND.
